US00D664139S

(12) **United States Design Patent**
Zheng et al.

(10) **Patent No.:** **US D664,139 S**
(45) **Date of Patent:** **** Jul. 24, 2012**

(54) **COVER OF AN ELECTRONIC DEVICE WITH SURFACE PATTERN**

(75) Inventors: **Du-Tong Zheng**, Shenzhen (CN); **Bin Li**, Shenzhen (CN)

(73) Assignee: **FIH (Hong Kong) Limited**, Kowloon (HK)

(**) Term: **14 Years**

(21) Appl. No.: **29/409,909**

(22) Filed: **Dec. 29, 2011**

(51) **LOC (9) Cl.** **14-03**

(52) **U.S. Cl.** **D14/248**

(58) **Field of Classification Search** ..... (57) **CLAIM**

The ornamental design for a cover of an electronic device with surface pattern, as shown and described.

DESCRIPTION

FIG. 1 is a perspective view of a cover of an electronic device with surface pattern showing our new design;

FIG. 2 is a front elevational view thereof; and,

FIG. 3 is a side elevational view thereof.

In the drawings, the broken lines indicate portions of the cover of an electronic device with surface pattern that form no part of the claimed design.
